Primary Examiner — Sandra Snapp*Assistant Examiner* — Leisha N Price(74) *Attorney, Agent, or Firm* — Muncy, Geissler, Olds and Lowe, P.C.(57) **CLAIM**

I claim the ornamental design for an inertial ring for hand tool, as shown and described.

DESCRIPTION

FIG. 1 is a right, front, and top perspective view of an inertial ring for hand tool showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a right, rear, and top perspective view thereof;

FIG. 9 is an environmental side view showing the inertial ring for hand tool in use; and,

FIG. 10 is an alternate environmental side view showing the inertial ring for hand tool in use.

The broken lines rendered in FIGS. 1-10 illustrate portions of the inertial ring for hand tool and form no part of the claimed design. The remaining broken lines rendered in FIGS. 9 and 10 illustrates the environment of the claimed design and form no part thereof.
